UNITED STATES PATENT OFFICE.

EDOUARD DEBRIE, OF PARIS, FRANCE.

SIGNAL-INDICATING DEVICE FOR RAILWAYS.

1,032,994.

Specification of Letters Patent. Patented July 16, 1912.

Application filed June 4, 1912. Serial No. 701,489.

To all whom it may concern:

Be it known that I, EDOUARD DEBRIE, a citizen of the French Republic, and a resident of 12 Rue des Capucines, Paris, France, merchant, have invented certain new and useful Improvements in and Relating to Signal-Indicating Devices for Railways, of which the following is a full, clear, and exact specification.

10 My invention has for its object a signal-indicating device for railways, and has more particularly in view to secure the transmission of the track-signals to the engine-driver, while providing a safety-device which causes 15 the automatic stopping of the railway-trains.

In order that my said invention may be fully understood and readily carried into practice by anyone skilled in the art, I will 20 now proceed to describe the same more particularly, reference being had to the accompanying drawings, forming part of this specification, in which similar letters of reference indicate corresponding parts throughout the several views, and in which:

Figure 1 is a perspective view of a railway-track provided with my device; Fig. 2 is a detail-view of the same; Figs. 3 and 4 are a front view and a vertical section respectively of the device intended to be built up on the locomotive; Fig. 5 shows this device in position on the locomotive; Figs. 6 and 7 are an end-view and a side-view respectively of an element of the controlling-device located upon the track; and Fig. 8 is a perspective view of the operating mechanism.

On the side of the track *a* and, preferably, parallel thereto is arranged an operating cable or rod *b* provided, at one of its ends, with a controlling-lever *c*, and carrying, at its other end, supported by a pulley *e*, a counterweight *d*. This cable has, at suitable intervals, operating-cams *f*, *g*, *h*, for instance three in number, corresponding to the number of the sections of protection provided between the distant-signal and the absolute stopping signal. These cams have suitably different lengths, and if it is assumed, for instance, that the trains are to be run in the direction of the arrow in Fig. 1, the length of the cam *h* being taken as the unit of length, the cam *g* shall have a double length and the cam *f* a triple one. Each of said cams may come into engagement with

a bell-crank lever *i* (Figs. 6 and 7) pivoted at *j* on the track and the free end *k* of which is suitably bent up.

On the locomotive and in the reach of the engine-driver is a slide-box *m* closed by a cover *n* having therein a vertical slot *o* through which can work a tappet *p* integral with a slide *q* located in the box *m* and the lower end of which rests upon a set of blocks or rollers *r* made of any breakable material, such, for instance, as porcelain, glass, burned earthenware or the like, and the lowermost one of which partially protrudes from the box through an aperture *s* in the latter.

In its raised position, the slide *q* conceals three differently colored disks *t*, *u*, *v*, located in the rear wall of the box *m* and said slide, being of suitably predetermined weight, has at its upper part, a hook *x* with which engages a cable or any other like member connected with the steam supply of the whistle 2 as shown in Fig. 3. The tappet *p* is adapted to come into contact, by its lower inclined face, with a bar *y* held in the position illustrated in Figs. 3 and 4 by a counterweight *z* and operating a cock *l* controlling the compressed air brake.

The working is as follows: For putting the apparatus into operative condition, the slide *q* is at first raised whereafter the rollers *r* are inserted into the box *m* through an aperture (not shown), which rollers are thus superposed to each other, in the position shown by dotted lines in Fig. 3. When all said rollers have been set into position, the slide *q* is dropped and thus held at a sufficient height for concealing the disks *t*, *u*, *v*. The lowermost roller *r* occupies now the position shown in Fig. 3, thus protruding a little distance below the lower edge of the box. When it is desired to order the engine driver to slacken the speed of the train or to call the attention of said driver to a track-signaling apparatus, the lever *c* is released so that the cam *f* comes into engagement with one of the levers *i*. Said lever assumes then the position shown by dotted lines in Fig. 6, and its end *k* places itself in the path of the roller *r* carried on the locomotive. When the latter reaches the point indicated by the signaling apparatus, the roller *r* strikes against the end *k* of the lever *i* which causes the breaking off of said roller. The fragments thereof fall down at once through the lower part of the box and a general

dropping of the remaining rollers and of the slide *q* takes place, this latter assuming the position shown in Fig. 3, wherein it leaves exposed the upper disk *t*, while causing at the same time a partial opening of the cock *b* of the whistle which calls the attention of the engine driver. When the latter has fulfilled the directions given by the disk or signaling apparatus, he puts again all the parts in their initial condition by lifting the slide *q* which he holds into its position by inserting a fresh roller into the box *m*. For transmitting a more imperative order, the lever *c* is released to a greater extent for the purpose of causing the lever operated by the cam *g* to be raised, the first cam continuing to act upon its own lever to hold the same in the position shown by dotted lines in Fig. 6, while the cam *g* brings also the corresponding lever into this same position. When the locomotive will have passed these two levers, two rollers *r* will have been broken, thus causing the slide *q* to drop, so as to uncover two disks *t*, *u*, and effecting at the same time a wider opening of the steam inlet cock of the whistle, whereby the sounding of the latter is altered and rendered more intense. At last, for ordering the absolute stopping, the lever *c* is completely released, whereby the three cams *f*, *g*, *h*, are brought into engagement with their respective levers for lowering each of them into the position shown by dotted lines in Fig. 6, so that, when the locomotive has passed the cam *h*, three rollers have been broken, thus causing the three disks *t*, *u*, *v*, to become exposed and further increasing the acuteness and intensity of the whistle sound. Simultaneously, at the time of the breaking of the third roller, the incline *p* of the slide *q* acts upon the handle *y* of the brake cock, to operate the brake.

This device secures a great reliability of working owing to the provision of weakly resisting rollers, the breaking of which will easily take place by their striking against the movable levers, and the different sounds uttered by the whistle will draw the attention of the engine driver, while indicating at the same time to him which signal he must obey. The cams *f*, *g*, *h* and the levers which they operate may be of any approved construction and their arrangement be varied according to the peculiar requirements. The box *m* might be located in any suitable place on the locomotive.

What I claim is:

1. In a signal indicating device for railway trains, a slide-box carried by the locomotive having an opening in its bottom, bodies of breakable material in said slide-box, means for holding the lowermost body protruding out through the opening of the slide-box; a lever arranged on the track for breaking the lowermost body and permit-

ting the ones located above to drop; and means for bringing said lever in the path of the lowermost breakable body.

2. In a signal indicating device for railway trains, the combination with a slide box having an opening in its bottom and inclosing superimposed breakable bodies, said box being provided with means for holding the lowermost body protruding through the opening of the box, of means for breaking the lowermost body protruding from the box, said means consisting of a group of levers, having operating cams, an operating rod or cable connected with said lever, and a lever on the side of the track for controlling said operating rod.

3. In a signal indicating device for railway trains, a box having an opening in its lower end, a plurality of superposed fragile bodies in the box, the box being provided with means for holding the lowermost one with its lower portion protruding through the opening in the bottom of the box, a slide in the box and resting on the uppermost fragile body, and a lever arranged on the track for breaking the lowermost fragile body.

4. In a signal indicating device for railway trains, a box having an opening in its lower end and an opening in one side of its upper end, colored disks in the box opposite the opening at the upper end thereof, a plurality of superposed fragile bodies in the box, the box being provided with means for holding the lowermost one with its lower portion protruding through the opening in the bottom of the box, a slide in the box and resting upon the uppermost fragile body and adapted to cover the opening in the upper part of the box, a lever arranged on the track for breaking the lowermost fragile body, and means for operating said lever.

5. In a signal indicating device for railway trains, a box carried by the locomotive, and having an opening in its bottom, a plurality of superposed fragile bodies in the box, the box being provided with means for holding the lowermost one with its lower portion protruding through the opening of the box, a slide in the box and resting upon the uppermost fragile body, means on the track for breaking the protruding fragile body, a whistle, and a connection between the whistle and slide for operating the former from the latter.

6. In a signal indicating device for railway trains, a box carried by the locomotive, said box having an opening in its bottom and an opening in one side of its upper end, a plurality of colored disks in the upper part of the box opposite the opening thereof, a plurality of superposed fragile bodies in the box, the box being provided with means for holding the lowermost one with its lower portion protruding through the opening in the bottom of the box, a slide

in the box and resting on the uppermost fragile body, said slide being adapted to cover the opening in the upper part of the box, means on the track for breaking the protruding fragile body, a whistle, a connection between the whistle and slide, a cock for controlling the air brake, and means for operating the cock from said slide.

7. In a signal indicating device for rail-way trains, a box carried by the locomotive and having an opening in its bottom and an opening in one side at the upper end, a plurality of colored disks in the box opposite the opening at the upper end thereof, a plurality of superposed fragile bodies in the box, the box being provided with means for holding the lowermost one with its lower

portion protruding through the opening in the bottom of the box, a slide in the box and resting upon the uppermost fragile body, the slide being adapted to close the opening at the top of the box, a plurality of levers on the track for breaking the fragile body protruding through the opening in the bottom of the box, an operating rod or cable, and a plurality of cams for successively operating the levers and operated by the rod or cable.

In testimony whereof I have hereunto affixed my hand this 24th day of May 1912.

EDOUARD DEBRIE.
